UNITED STATES PATENT OFFICE

120,464

DESIGN FOR AN ADAPTER FOR A CONTAINER CLOSURE

Herman H. Martin, Toledo, Ohio, assignor to
H. H. Martin Products Corporation, Toledo,
Ohio, a corporation of Ohio

Application May 22, 1939, Serial No. 85,118

Term of patent 14 years

To all whom it may concern:

Be it known that I, Herman H. Martin, a citizen of the United States, residing at Toledo, Lucas County, Ohio, have invented a new, original, and ornamental Design for an Adapter for a Container Closure, of which the following is a specification, reference being had to the accompanying drawing, forming a part thereof, in which the figure is a perspective view of an adapter for a container closure showing my new design.

I claim:

The ornamental design for an adapter for a container closure, substantially as shown.

HERMAN H. MARTIN.
